CALCULATING MACHINE

Arthur J. Fettig, Detroit, Mich., assignor to
 Burroughs Adding Machine Company, Detroit,
 Mich., a corporation of Michigan

Application July 9, 1937, Serial No. 152,703

18 Claims. (Cl. 101—93)

This invention relates to calculating machines and is particularly concerned with the printing mechanism thereof whereby so-called safeguard symbols or characters may be automatically printed to the left of the printed amount in order to prevent alteration of the amounts as entered.

The invention is particularly adaptable for use in check-writing machines and such and may be considered as an improvement over the mechanisms disclosed and described in the Bentzel Patent No. 1,958,464 and the Muller Patent No. 1,997,073 although the invention is illustrated as applied to a different type of machine. As stated in these two prior patents it is frequently desirable to be able to print characters in the higher orders to the left of the printed amount including printing a currency sign in the highest order to the left, all without affecting printing of zeros in those same banks if they should lie to the right of the last order indexed when some other amount is printed.

It is a general object of the invention to provide an improved calculating machine.

A more particular object is to provide a calculating machine in which the character or safeguard printing automatically occurs in the desired columns in both listing and totaling operations, and regardless of which register is being utilized in a multiple register machine and of course regardless of whether the printing occurs in response to amounts indexed by key depression or in response to the totals contained in a register.

Other and more particular objects will appear from the following specification and drawings illustrating an embodiment of the invention and in which,

Figure 1 is a left side sectional elevation of a calculating machine embodying the present invention, the parts being illustrated in normal position;

Fig. 2 is a perspective view illustrating portions of two orders of the machine, the elements thereof being in normal position and certain orders of the printing mechanism being omitted for clearness;

Fig. 3 is a rear elevation of the portion of the type bearing members illustrating the type when indexed to print \$1,200.00;

Fig. 4 is an enlarged left side detail of a portion of the differential mechanism of a single column showing the actuator rack indexed or moved to zero printing position;

Fig. 5 is a view similar to Fig. 4 but illustrating the actuator bar moved beyond zero position;

Fig. 6 is a view similar to Fig. 4 but illustrating one actuator bar returned to normal character printing position.

Fig. 7 is a sample of work performed by a machine embodying the present invention when controlled during the taking of totals and sub-totals; and

Fig. 8 is a sample of work performed by the same machine when controlled by a listing operation with the amounts set up on the keyboard. 10

General construction

The invention is illustrated as applied to a Burroughs calculating machine which may be used as a bookkeeping machine and also as a checkwriting machine. This type of machine is well known in the commercial field and is illustrated in many patents, one type of such machine being shown in the Gooch Patent No. 1,395,044, issued October 25, 1921.

Referring to Fig. 1, the illustrated machine may be either a hand operated or power driven machine and is provided with nine banks of depressible amount keys 1, the number of banks being varied in different machines to suit the requirements. Items are entered by depressing the keys and as each key is depressed its stem is moved into the path of a projection 2 of its associated index bar 3. These index bars which connect the type sectors and register actuator racks as will be described later correspond in number to the orders or banks of amount keys are supported for horizontal movement, are normally urged forward or to the right (Fig. 1) by springs, and are provided at their forward ends with toothed actuator racks 4 and 5 which are slidingly attached to the bars by pin and slot connections which permit of one step of movement of the racks relative to the bars, as described in the Peters Patent No. 1,255,821. This relative movement between the racks and bars is primarily for the purpose of a tens transfer but is taken advantage of for an additional purpose in the present invention. Racks 4 and 5 engage an upper register or cross footer 6 and a lower register 7, respectively, although a single register only may be employed, if desired. Each of the registers 6 and 7, when two registers are employed, are moved into and out of engagement with the toothed racks 4 and 5, respectively, in proper time relation by a mechanism similar to that disclosed in the Gooch Patent No. 1,327,318 or may be moved by mechanism similar to that shown in the Peters Patent No. 1,255,821, or as 55

illustrated in my co-pending application, Serial No. 182,056, filed December 18, 1937.

At their rear ends bars 8 are secured to type sectors 8 urged counterclockwise by springs and returned by a bail 9. The type sectors 8 carry type 11 which are driven against the platen P by type hammers 12. The hammers are spring urged toward the platen and are latched away from the platen by hammer latches 13 which are rocked clockwise by a pawl 14 carried by a swinging ball (not shown) during the latter portion of the forward stroke of the machine to release the hammers and cause printing. There is, of course, a hammer latch 13 and a pawl 14 for each order. 15 Each pawl 14 except the third lowest or dollars order pawl is provided with a tail 16 that engages the type sectors in such a manner that if the type bar is not raised above zero position the pawl will not release the hammer latch, whereas if the 20 type bar is raised above zero position the pawl is permitted to rock clockwise and to engage its latch to release the latter at the end of the forward stroke of the machine. The three lowest order latches 13 are of course operated at every 25 machine operation because the pawl 14 of the third lowest order has no tail 16 and therefore operates its latch 13 in every operation of the machine. This mechanism is not described in greater detail, being shown in the Gooch Patent 30 No. 1,395,044 to which reference is made for further description. A platen P is mounted upon a traveling paper carriage G supported by guide rails 17 and is normally urged to the right, as the machine is faced by the operator, by spring drum 35 and is tabulated to the left by power mechanism (not shown) for columnar printing.

As stated and as shown in Fig. 3, the present machine is provided with nine banks or orders. The type bars of the first three orders are not 40 provided with character or safeguard type whereas the remaining six higher orders are provided with the character type, i. e., five orders are provided with an asterisk and the sixth or highest order is provided with a currency sign or \$ type. 45 The character type including the \$ type lie immediately above or adjacent the zero type in all orders in which a character type is provided. The normal position of the type sectors of the six highest orders is with the end or character 50 type at the printing line and the cipher type one space below the printing line, and of the three lower orders, with the blank spaces at the printing line and the cipher type one space below the printing line so that, if printing were to occur 55 with all type in their normal or home positions, characters would be printed in the six higher orders but nothing would be printed in the three lower orders. When the machine is operated either by hand or motor power all type sectors 60 shift one type space to move the zero type in all orders to the printing line. The type carrying sectors of the highest six orders are then returned to character printing position in those orders which are not indexed by key depression 65 or by the register pinions.

Printing occurs at the end of the forward stroke of the machine which may be accomplished either by a hand crank or an electric motor (not shown). At the end of the return stroke the type bars and actuator racks are returned to normal position by a bail 9 as described in the Gooch patent.

No movement takes place in the register during this preliminary movement of the type sectors and index bars because of the sliding con-

nection between the index bars and the racks which permits limited movement of the index bars relatively to the racks.

Type of work performed

5

In order to facilitate an understanding of this invention and particularly as to its work, a class of work for which it is especially suited will first be described in connection with Figs. 7 and 8. 10 Referring first to Fig. 7, there is illustrated a portion of a continuous journal sheet J which is placed around the platen and which contains a printed record of all transactions entered in the machine. A check or work sheet W which 15 may be either in the form of an individual check or a sheet of checks as are used by many employing commercial bookkeeping systems are also placed around the platen. When recording the complete transaction the gross amount is 20 first entered on the journal sheet by entering the amount on the keyboard and operating the machine which causes the amount to be printed and the carriage automatically to be tabulated to the second columnar position where the deductions are entered upon the keyboard and in 25 which column the machine is again operated. This causes the deduction to be printed after which the machine tabulates into the third column on the journal. In this position the 30 subtotal key is depressed which causes the total or difference between the gross amount and the deduction to be printed after which the carriage tabulates to the next column or first position on the check. In this position the dollars only are 35 automatically printed, printing of the cents being prevented by a hammer block mechanism, after which the carriage tabulates to the next column or second check position where the cents only are printed. In this column the variable 40 hammer block mechanism again functions to eliminate printing of everything but the cents. The carriage then automatically moves to the last column or third position on the check where the full amount of the check is again printed 45 by depression of the total key which automatically clears the upper register or cross footer.

The present invention causes safeguard symbols or characters such as asterisks to be printed to the left of the amounts in the first and last 50 check printing positions. The safeguard printing includes printing a dollar sign (\$) in the highest order in these two carriage or columnar positions.

Referring to Fig. 8, for a slightly different 55 type of transaction a single amount is entered upon the keyboard with the carriage in the second columnar position, and the keys remain depressed through the remaining operations as the carriage tabulates for repeat operations in the 60 three columnar positions of the check in which the variable hammer block mechanism functions as mentioned in connection with Fig. 7 and in which characters or symbols are printed to the left of the last indexed bank in the first and last columnar positions of the check. These two types of work which may be performed upon the machine illustrate that the character printing occurs to the left of the highest indexed order 70 regardless of whether the printing is in response to the register pinions or depressed amount keys. This is accomplished by placing the character printing under control of the type sectors or index bar or rack movement.

75

Character printing to the left of the highest order indexed

The printing of characters or "safeguard" printing is placed under control of movement of the type sectors or indexing bars which remain in normal or home position until after operation of the machine has started. After movement of the index bars beyond cipher position, the "safeguard" symbol mechanisms are made effective. This arrangement makes it possible to adapt this feature to all types of machines with one or more registers and to utilize the feature in connection with total printing and/or listing. In other words, the invention is very flexible.

As previously stated, the illustrated machine is a nine column printing capacity machine and all type sectors above the dollars order are provided with an asterisk or character type, except the highest order which is provided with a dollar sign (\$) type, located directly above the zero type. In Fig. 2, two orders, the third and ninth or highest, of the machine are illustrated, two non-adjacent columns being selected in order to show the mechanisms more clearly.

Each index bar 3 is provided with a flat stud 20 projecting laterally from its left side and overlying a pawl 21 pivoted at 22 to a bracket 23 and urged counterclockwise by a spring 24. Counterclockwise movement of pawl 21 is limited by its downwardly projecting lug 25 engaging a fixed bar 26. The bracket 23 is secured to a plate 27 supported on two shafts 28 slidably supported at the front and rear by brackets 29. Secured to shafts 28 adjacent their rear ends is a cross bar 31 to which is secured the forward end of a link 32, the latter being supported for horizontal movement by a shaft 33. The rear end of link 32 is provided with an upstanding foot 34 in position to be engaged by a stud 35 carried by an arm 36 secured to the main driving shaft 37. Intermediate its ends link 32 is also provided with an upstanding arm 38 which carries a stud 39 in position to engage a cam 40 journaled on the secondary shaft 41 and connected by a spring 42 to an arm 43 fixed to shaft 41. This provides a yielding connection between cam 40 and shaft 41 for purposes later to be described.

Plate 27 together with bar 31, shafts 28, brackets 23 and pawls 21 constitute an assembly which is normally urged to the rear or to the left (Fig. 2) by tension springs 45. The assembly is normally prevented from moving to the rear by engagement of stud 39 with cam 40 which holds link 32 and the bar 31 with the attached assembly in its forward position.

As the machine is given a stroke of operation either by depressing a motor bar or pulling upon an operating handle all the index bars 3 are released for forward movement. In those orders not indexed by depression of the amount keys, the bars move forwardly a distance of one type which is sufficient to move the type sectors from their normal or home position to zero or cipher printing position (Fig. 4). In those orders which are indexed by depression of an amount key, the bars move to full indexed position (Fig. 5). As previously stated, no movement of the racks 4 or the register pinions occurs in those orders in which the bars are moved from normal to zero printing position because of the slotted connection between the index bars and the racks. Studs 20 of those bars which have been moved beyond zero position will have moved beyond the rear edge of shoulder pieces 47 (Fig. 5) and

will be unaffected thereby; but studs 20 of those bars in the orders which have not been moved beyond zero (Fig. 4) will lie in the path of shoulder pieces 47 secured to each of pawls 21. That is, they will project slightly above the top edge of the pawls and will be engaged thereby, as will now be explained.

As the machine continues to operate, cam 40 will be rotated clockwise and permit the stud 39 to drop first to the low portion of the cam which permits pawls 21 to move away from bar 26 whereby pawls 21 will be rocked counterclockwise by their springs into engagement with studs 20. After this movement and upon further operation of the machine, cam 40 rotates clear of stud 39. This will permit springs 45 to retract plate 27 and its associated assembly, including pawls 21. As pawls 21 move rearwardly under influence of their springs 24, they will engage those studs 20 of actuators which were moved to zero position only and will return those actuators rearward to normal position with the character type at the printing line. It will be understood, of course, that as the machine is operated and as shaft 41 is rotated main shaft 37 will also be rotated and withdraw stud 35 from foot 34 of slide 32 and that the registers are not engaged with the actuator racks at this time.

As previously stated, any index bar 3 that is moved forward beyond zero position will carry its stud 20 beyond the effect of shoulder piece 47 and these actuator racks will not be affected by the rearward movement of plate 27 and its assembly. In other words, as illustrated in Fig. 3, in entering the amount of \$**1200.00 the three highest order type bars are moved from their downward or normal character printing position to their zero printing position and then back to character printing position during the forward machine stroke and before printing occurs. On the other hand, the fifth and sixth orders containing the digits of value are moved to and remain in their indexed 2 and 1 positions, respectively.

It is not desirable to have a character inserted between the figures of the printed amount and accordingly the printing of characters is disabled to the right of the highest order indexed. For example, although the fourth order is not indexed beyond its zero position, it remains at zero position instead of being returned to character printing position. This is accomplished by a lateral projection 50 which projects from the left side of each pawl 21 and underlies a projection 51 extending from the right of each adjacent higher order pawl. Accordingly, in an order where the pawl 21 is not allowed to rock counterclockwise because the stud 20 of an indexed rack overlies the pawl, its projection 51 will prevent rocking of pawl 21 in the next adjacent lower order and so on down through the lower orders excepting the first three orders of the machine, which, of course, have no character type. By this means all pawls 21 associated with all orders (excepting the three lowest orders) below the highest indexed order to the left will be prevented from rocking counterclockwise and will accordingly be prevented from becoming effective; that is, the pawls 21 of all orders to the right of the highest indexed order to the left will be disabled.

As previously stated near the end of the forward machine stroke cam 40 clears stud 39 and link 32 moves rearwardly until limited by engagement with stop 52 during which time all type bars to the left of the amount indexed are

- returned from their zero printing to their character printing position. At the extreme end of the forward machine stroke printing occurs after which the machine is restored to normal position.
- 5 Although cam 40 is positively driven in a clockwise direction during the forward machine stroke, cam 40 can yield during the return stroke, because of a spring 42 and will retain the assembly moved by plate 27 in rearward position until the 10 extreme end of the returned stroke. At this time stud 35 on the main driving shaft 37 engages the footed end 34 of link 32 and restores link 32 and the assembly carried by plate 27, against the action of springs 45, to its forward or normal 15 position. As link 32 moves forwardly stud 39 will also move forwardly and permit spring 42 to return cam 40 clockwise to its normal position rearwardly of stud 39.

Carriage control

- 20 Provision is made for carriage control of character printing to the left of the highest order indexed. It will be understood from the invention thus far described that the slide 27 and its assembly is moved rearwardly and returned to normal position at each machine operation. Accordingly, if the printing hammers were released at each machine operation printing would occur and characters would be printed to the left of the 25 highest order indexed at each machine operation. 30 A carriage control of the printing hammers is provided whereby character printing is restricted to certain columnar positions of the carriage.

For this purpose the traveling paper carriage 35 C (Fig. 1) is provided with rollers 75 positioned on the carriage so as to engage one arm of a crank 76 in predetermined columnar positions of the carriage. Crank 76 is pivoted at 77 and its other arm is connected to the upper end of a 40 vertical link 78, the lower end of which is connected to one arm of a crank 79 pivoted at 80 to the frame of the machine. Another arm of crank 79 is connected to a horizontal link 81 (Figs. 1 and 2) which extends toward the front of the 45 machine where it is connected to one arm of a crank 82 pivoted at 83 to a bracket 84. The other arm of crank 82 is provided with a horizontal extension 86 positioned to engage the foot of a pawl 87 pivoted to the hammer latch 13 of an intermediate order, the dollars order in the 50 illustrated machine which order is operated in every operation of the machine. It will be understood that the pawl 87 could be pivoted to any desired hammer latch and is attached to the 55 dollars order in the present machine because the illustrated machine is designed particularly for check writing purposes. Pawl 87 is provided with a lateral extension 89 which spans the remaining intermediate printing hammers and engages a 60 shoulder of a pawl 90 pivoted to latch 13 for the highest order printing hammer. For sake of clearness, several orders of the hammers and associated mechanism have been omitted from Fig. 2 and it will be seen from this figure that extension 89 of pawl 87 extends from the third or 65 dollars order to the ninth or highest order and skips the intervening orders. The arrangement and construction is such that when latch 13 of the dollars order is rocked with pawl 87 in low- 70 ered position its extension 89 will engage the shoulder of pawl 90 and rock latch 13 of the highest order and release hammer 12 of the highest order. The hammer latches 13 are provided with lower tails 91 which project laterally 75 and engage the adjacent lower order latch so that

all latches down from the highest order latch released will be released as described in the Gooch Patent 1,395,044.

As previously stated, to prevent or disable the printing of characters to the left of the highest indexed order carriage roll 75 is positioned so as to engage crank 76 in each columnar position in which it is desired to eliminate character printing. The effect of such a roll is to rock crank 82 counterclockwise (Fig. 2) which will cause its foot 86 to raise pawl 87 and disengage its extension 89 from pawl 90. When pawl 87 is in raised position, release of hammer latch 13 of the third or dollars order will not cause a release of the hammer latch 13 of the highest order or of the intervening orders between the highest order and the dollars order.

Variable hammer block mechanism

20 It will be observed from Figs. 7 and 8 that in the first column of the check, printing of the cents is omitted and in the second column of the check, printing of the dollars is omitted. This is accomplished by the variable hammer block mechanism which in the illustrated machine comprises a 25 four-bladed shaft 100 (Fig. 2) positioned over fingers 101 projecting forwardly from the type hammers. The blades of the shaft are formed and cut out so as to block or latch certain desired hammers in each position of the shaft to prevent 30 their release even though the hammer latches may be released. Shaft 100 is rotated by means of a gear 102 on the end of the shaft which engages a rack 103, the latter being moved in accordance with and under control of the carriage. 35 For this purpose rack 103 is connected to a horizontal pivoted lever 104 extending to the rear of the machine where it is connected by a vertical link 106 to a control cam 107 engaged by different sized rolls 108 on the carriage which cause rack 103, gear 102 and blades 100 to be rotated to its four different positions corresponding to the carriage positions.

The illustrated machine is particularly well suited for printing cancelled checks where the checks are printed in strip form and it is desired to cancel some intermediate check as, for example, where the amount involved would be less than a dollar and it is not desired to issue a 50 check for less than a dollar. The present machine provides that a series of zeros can be printed in the first three columns, and characters printed in the higher orders to automatically cancel the check. This can be accomplished by causing the hammers to fire during each and 55 every operation of the machine regardless of whether an amount was indexed or not. To accomplish this it is merely necessary to omit the lug 16 of the hammer latch pawl 18 of the third or dollars order so that the hammer of this 60 order fires at each operation. This would of course, cause printing of zeros in the third and lower orders and printing of characters in the highest and intermediate orders between the highest order and the dollars order.

I claim:

1. A calculating machine having a cooperative plural order mechanism comprising a plurality of depressible keys, a group of associated index bars controlled thereby, a printing mechanism comprising a corresponding and associated group of type carrying members controlled by said keys and supporting type, mechanism for causing said type to print, and means associated with an intermediate order of said latter mechanism and act-

ing directly upon a non-adjacent higher order of said mechanism to cause said type in said group to print in said higher order.

2. A calculating machine having in combination a plurality of associated banks of depressible keys, a group of associated index bars controlled thereby, a printing mechanism comprising a corresponding associated group of type carrying members controlled by said keys and sup-

10 porting type including a special character type, means for causing said type to print, and means associated with an intermediate order mechanism of said machine and acting directly upon a non-adjacent higher order mechanism of the machine 15 to cause said type in said group to print a character in said higher order.

3. In a calculating machine having a plurality of depressible keys, a plurality of index bars associated therewith, the combination with

20 a plural order printing mechanism comprising printing type having character type in the higher orders, means for normally conditioning said printing mechanism to print to the right and not to the left of the last order in which a digit is indexed, of means conditioned by an intermediate order mechanism of the machine moved during a machine operation and automatically operable directly upon a non-adjacent higher order mechanism of the machine to cause said printing type 30 to print a character in said higher order.

4. In a calculating machine having a plurality of depressible keys, a plurality of index bars associated therewith, the combination with a plural order printing mechanism comprising printing

35 type having character type in the higher orders, means for normally conditioning said printing mechanism to print to the right and not to the left of the last order in which a digit is indexed, of means controlled by an intermediate order 40 mechanism of the machine moved during the machine operation non-adjacent to the highest order mechanism of the machine and automatically operable directly upon the highest order mechanism of the machine to cause said printing type to print a character in said highest order.

5. In a calculating machine having a plurality of depressible keys, a plurality of index bars associated therewith, the combination with a plural

50 order printing mechanism comprising printing type normally positioned to print characters in the higher orders and movable during operation of the machine to print ciphers in all orders, means for normally conditioning said printing 55 mechanism to print to the right and not to the left of the last orders in which a digit is indexed, of means conditioned by an intermediate order mechanism of the machine moved during the machine operation and automatically operable directly upon a non-adjacent higher order to cause said printing type to print a character in said higher order whereby characters are printed to the left of the last order to the left in which a digit is indexed.

65 6. In a calculating machine having a plurality of depressible keys, a plurality of index bars associated therewith, the combination with a plural order printing mechanism comprising printing type normally positioned to print characters in

70 the higher orders and movable during operation of the machine to print ciphers in all orders, means for normally conditioning said printing mechanism to print to the right and not to the left of the last orders in which a digit is indexed, 75 of means conditioned by an intermediate order

mechanism of the machine moved during a machine operation non-adjacent to the highest order mechanism of the machine and automatically operable directly upon the highest order mechanism of the machine to cause said printing type to print a character in said highest order whereby characters are printed to the left of the last order to the left in which a digit is indexed.

7. A calculating machine having in combination a plurality of depressible keys, a plurality of index bars controlled thereby, a printing mechanism comprising plural order type carrying members controlled by said keys and supporting type, means for causing said type to print, a latch for each order of type, and means associated with an intermediate order latch and acting directly upon a non-adjacent higher order latch to cause said type to print in said higher order.

8. A calculating machine having in combination a traveling paper carriage, a plurality of depressible keys, a plurality of index bars controlled thereby, a printing mechanism comprising plural order type carrying members controlled by said keys and supporting type, means for causing said type to print, means associated with an intermediate order mechanism of the machine and acting directly upon a non-adjacent higher order mechanism of the machine to cause said type to print in said higher order, and connections between said carriage and said latter means for controlling printing in said higher order.

9. A calculating machine having in combination a traveling paper carriage, a plurality of depressible keys, a plurality of index bars controlled thereby, a printing mechanism comprising plural order type carrying members controlled by said keys and supporting type including a special character type, means for causing said type to print, means associated with an intermediate order mechanism of said machine and acting directly upon a non-adjacent higher order mechanism of the machine to cause said type to print in said higher order, and connections between said carriage and said latter means for controlling printing in said higher order.

10. In a calculating machine having a plurality of depressible keys, a plurality of index bars associated therewith, a traveling paper carriage, the combination with a plural order printing mechanism comprising printing type having character type in the higher orders, means for normally conditioning said printing mechanism to print to the right and not to the left of the last order in which a digit is indexed, of means conditioned by an intermediate order mechanism of said machine non-adjacent the highest order moved during the machine operation and automatically operable directly upon a non-adjacent higher order mechanism of the machine to cause said printing type to print a character in said higher order, and connections between said carriage and said latter means for controlling printing in said higher order.

11. In a calculating machine having a plurality of depressible keys, a plurality of index bars associated therewith, a traveling paper carriage, the combination with a plural order printing mechanism comprising printing type normally positioned to print characters in the higher orders and movable during operation of the machine to print ciphers in all orders, means for normally conditioning said printing mechanism

to print to the right and not to the left of the last orders in which a digit is indexed, of means conditioned by an intermediate order mechanism of the machine moved during the machine operation and automatically operable directly upon a non-adjacent higher order mechanism to cause said printing type to print a character in said higher order whereby characters are printed to the left of the last order to the left in which a digit is indexed, and connections between said carriage and said latter means for controlling printing in said higher order.

12. A calculating machine having in combination a traveling paper carriage, a plurality of 15 depressible keys, a plurality of index bars, a printing mechanism comprising plural order type carrying members controlled by said keys and supporting type, means for causing said type to print, a latch for each order of type, means 20 associated with an intermediate order latch and acting directly upon a non-adjacent higher order latch to cause said type to print in said higher order, and connections between said carriage and said latter means for controlling printing in said 25 higher order.

13. In a calculating machine having a plurality of banks of depressible amount keys, a plurality of index bars associated therewith, a plural order printing mechanism comprising type sectors 30 having normal printing positions, means operable during an operation of the machine for moving the type sectors of all orders in one direction from normal position to present a different type at the printing line, and means automatically operable in certain orders of said 35 machine in which no key has been depressed to cause the type sectors in those latter orders to be returned to normal printing positions.

14. In a calculating machine having a plurality of banks of depressible amount keys, a plurality of index bars associated therewith, a plural order printing mechanism comprising printing type sectors having normal printing positions, means operable during an operation of the machine for moving the type sectors of all orders 40 in one direction from normal printing position to present a different type at the printing line, and means controlled by said index bars and automatically operable in certain orders of said 45 machine in which no key has been depressed to cause the type in those latter orders to be returned to normal printing positions.

15. In a calculating machine having a plurality of banks of depressible amount keys, a plurality of index bars associated therewith, a plural order printing mechanism comprising printing type sectors having a normal printing position, means operable during an operation of the machine for moving the type sectors of all orders 50 in one direction from normal positions to present a different type at the printing line, means automatically operable in certain orders of said machine in which no key has been depressed to cause the type in those latter orders to be returned to normal printing positions, and means 55 automatically operable to prevent said return movement in orders to the right of the last order to the left in which an amount is indexed.

16. In a calculating machine having a plurality of banks of depressible amount keys, a plurality of index bars associated therewith, a plural order printing mechanism comprising printing type sectors having normal printing positions, means operable during an operation of the machine for moving the type sectors of all orders in one direction from normal positions to present a different type at the printing line, means controlled by said index bars and automatically operable in certain orders of said machine in which no key has been depressed to cause the type sectors in those latter orders to be returned to normal printing positions, and means automatically operable to prevent said return movement in 10 orders to the right of the last order to the left in which an amount is indexed.

17. In a calculating machine having a plurality of banks of depressible amount keys, a plurality of differentially movable racks controlled by said amount keys, a plural order printing mechanism comprising type sectors having digit, cipher, and special character types thereon and adapted to print along a printing line, said type sectors having a normal home position with the end type 20 thereon at the printing line, connecting members between said racks and said type carriers, said connecting members being constructed and arranged to permit the type carriers to move one step from their normal positions before movement of said racks to present the type adjacent the end type to the printing line, and means for returning to home position the type carriers and connecting members in those orders in which no digit from 1 to 9 is indexed and which are at a 25 predetermined side of the highest order type carrier which is set to print a digit from 1 to 9.

18. The combination in a calculating machine having means for giving it cycles of operation, a plurality of banks of amount keys, an index bar 40 for each bank controlled by the keys of its bank, a type bar operatively connected to each index bar, said type bars normally being positioned with blank spaces along the printing line and all of said type bars normally being moved one 45 space relative to said printing line during a machine cycle to bring "0's" to the printing line in all orders where digits are not indexed, and a printing mechanism normally operable during a 50 machine cycle to cause printing only in orders to the right of the highest order in which a digit is indexed; of special character type positioned in the blank spaces on certain of the higher orders of said type bars, means controlled by said index bars and operating during a machine cycle 55 to cause all the type bars in the orders above the highest order in which a digit is indexed to be returned to normal prior to a printing operation, normally ineffective printing control means governed by an intermediate lower order of said 60 printing mechanism for causing the printing mechanism to operate in all the orders higher than said intermediate order, and means for rendering said printing control means effective, whereby special characters will be printed to the 65 left in the orders above the highest order in which a digit is indexed.

ARTHUR J. FETTIG.
